By *James V. Ramsey*

ATTORNEY

UNITED STATES PATENT OFFICE.

ERNEST MEIERJOHAN, OF CINCINNATI, OHIO.

AUTOMATIC CUT-OUT.

Application filed April 18, 1922. Serial No. 555,205.

To all whom it may concern:

Be it known that I, ERNEST MEIERJOHAN, residing in Cincinnati, in the county of Hamilton and State of Ohio, have invented 5 certain new and useful Improvements in Automatic Cut-Outs, of which the following is a specification.

My invention relates to improvements in automatic cut outs adapted for repeated 10 use.

The objects of my invention are to provide an automatic cut out of simple efficient and inexpensive construction which is adapted to be used indefinitely without damage 15 by short circuit or overload, and to provide means whereby a shorted plug can be detected immediately by means of a lighted portion when the circuit is broken.

With these and other objects in view my 20 invention consists in the novel features of construction and in the combination and arrangement of parts as herein set forth and claimed, but it will be understood that certain modifications can be made without departing from the scope or spirit of the 25 claims.

In the drawings:

Fig. 1 is a side elevation of the preferred 30 construction partly broken away to show the interior;

Fig. 2 is a longitudinal section partly in elevation, taken on the line 2—2 of Fig. 3;

Fig. 3 is a plan view of Fig. 1;

Fig. 4 is a longitudinal section taken on 35 the line 4—4 of Fig. 3 the inner working parts being shown in elevation;

Fig. 5 is an enlarged longitudinal section of one end of Fig. 2 showing a modification;

Fig. 6 is a plan and perspective view of 40 the stop collar;

Fig. 7 is a perspective view of the dial which indicates the different amperes;

Fig. 8 is a perspective view of the dial 45 supporting and operating sleeve;

Fig. 9 is a perspective view of a cartridge type of cut out;

Fig. 10 is a longitudinal section partly in 50 elevation, taken on the line 10—10 of Fig. 12;

Fig. 11 is a longitudinal section partly in elevation, taken on the line 11—11 of Fig. 12;

Fig. 12 is a plan view of Fig. 11 with 55 cap 39 removed; and

Fig. 13 is a perspective view of the inner working parts of this style of cut out.

In the embodiment of my invention as illustrated and which shows preferred constructions I provide a porcelain housing or receptacle 1 having a porcelain cap 2 provided with central hole 2' and suitably seated thereon and secured thereto by porcelain cement 3. Spring circuit connection 4 inserted through hole 5 in porcelain housing 1 is attached to a coarse screw threaded brass shell 6 for insertion in any suitable electric socket. Housing 1 is provided in its reduced end with a hole 7 to receive holding screw 8 to which the interior working parts are attached. Said screw has a reduced stem 9 adapted to fit socket 10 in one end of insulating fibre pin 11 which has its other end supported in ear 12' of U-shaped bracket 12. Said bracket is seated in the reduced end of porcelain housing 1 and is held in place therein by holding nut 13 on screw 8.

Spring finger 14 of U-shaped bracket 12 is curved outwardly at 15 to permit it to yield under pressure and at its upper end is provided with an inturned lip 16 having beveled end 16' adapted to slide over and rest upon outwardly tapered shelf 17' of collar 17 fixed on fibre pin 11 within bracket 12. Said shelf acts as a stop to limit the outward movement of fibre pin 11 and also to engage lip 16 to hold fibre pin 11 in circuit clamping position as shown in Fig. 2. Holding nut 13 has a conducting wire 18 embedded therein and extending therefrom into engagement with lip 16 and is preferably insulated from spring finger 14 by insulating plate 19 interposed therebetween and between holding nut 13 on one side and U-shaped bracket 12 and boss 8' of screw 8 on the other side. Coil spring 20 encircling stem 9 is interposed between holding nut 13 and fibre pin 11 and is adapted to operate as hereinafter set forth. 100 Screw 8 is insulated from engagement with U-shaped bracket 12 by insulating bushing 8''. A tapered collar 21 of copper or other suitable conducting material is rigidly mounted upon fibre pin 11 for the purpose 105 of engaging the free end of spring connection 4 and tapered lug 22 supported by arm 23 rigidly attached to one side of bracket 12.

When the parts are in the positions in- 110

dicated in Figs. 2 and 4, the device is screwed into a socket to make electrical connection with the circuit it is to serve, and when there is a short circuit or overload the 5 current passes through screw 8 into holding nut 13 and wire 18, then into spring finger 14 of U-shaped bracket 12 to arm 23 into lug 22, then into tapered collar 21, then into spring connection 4, and coarse screw 10 threaded brass shell 6 thereby completing the circuit, whereupon the abnormal current passing through wire 18 will heat it sufficiently to cause it to expand lengthwise thereby pressing outwardly against spring 15 finger 14 and forcing lip 16 out of engagement with shelf 17' of stop collar 17. Coil spring 20 will then force fibre pin 11 and collar 17 lengthwise into engagement with arm 12' and tapered collar 21 lengthwise 20 into the disengaged position shown in Fig. 1 thereby breaking the circuit.

Fig. 5 shows a modified construction which takes care of different rates of flow of current as, for instance, in this view the 25 rate may be changed from 5 to 20 amperes. To accomplish this I provide a sleeve 24 having knurled knob 25 upon its outer end and flange 26 upon its inner end with key 27 extending longitudinally therethrough, 30 so that when said sleeve is inserted in hole 2' of cap 2 upon fibre pin 11, said key 27 will engage key way 28 of fibre pin 11 whereby it is adapted to be rotated. A bell shaped dial 29 having tubular bearing 29' 35 is fixed on sleeve 24 directly beneath porcelain cap 2 and has numbers 30 arranged thereon at distances apart as shown in Fig. 7 whereby one number at a time may be seen through observation hole 31 in cap 2. 40 The inner wall 32 of said dial is provided with indentations 33 adapted to engage spring 34 secured to housing 1 to hold said dial in any desired adjusted position.

Stop collar 35 has a cam shaped head 36 45 adapted to engage lip 16 so that when dial 29 is turned to bring the number 5 into view through observation hole 31 collar 35 is in position so that lip 16 rests on the narrowest part of cam shaped head 36 thereby taking care of small amperes. When it is desired to change this plug so as to take care of heavier duty simply turn knurled knob 25 until the desired number on dial 29 may be seen through observation hole 31 thus turning cam shaped head 36 and increasing the hold of lip 16. By thus increasing said hold 55 spring finger 14 must be moved a greater distance thereby requiring wire 18 to become hotter in order to expand far enough 60 to release collar 35 and break the circuit. Fibre pin 11 is provided with radium 37 which is concealed within the housing and is only visible when the circuit is broken thus indicating an overcharge and open circuit. The cap 2 of the housing is prefer-

ably made of white enamel or porcelain and is adapted to form a reflector for the radium 37.

Ear 12' receives sleeve 24 and engages flange 26 thereon to hold said sleeve and 70 bell in spaced apart relation from cap 2.

In the modified construction shown in Figs. 9, 10, 11, 12 and 13 I provide a cylindrical housing 38 made of heavy paper or any other suitable non-conducting material 75 and having an elongated opening 38' therethrough. Metal conducting terminal caps 39 and 40 are placed over the ends of said housing and cap 40 is provided with hole 41 in which screw 42 is inserted. Said screw 80 connects and supports the interior working parts.

L-shaped conducting bracket 43 is mounted on screw 42 and is insulated from cap 40 by insulation 44. Holding spring 45 is mounted upon screw 42 and is insulated 85 from L-shaped bracket 43 by insulation 46. It is also insulated from holding nut 47 by insulation 48. Screw 42 is insulated from L-shaped bracket 43 and holding spring 45 by insulating bushing 49'. The free end of holding spring 45 has an in-turned beveled lip 49 adapted to engage L-shaped bracket 43. Holding nut 47 has a wire 50 embedded therein and extending 90 therefrom into holding engagement with lip 49. Fibre pin 51 extending through elongated opening 38' is inserted in the upper end of L-shaped bracket 43 and has copper circuit cap 52 rigidly fixed thereon. Fibre 95 pin 51 has radium 53 thereon which is only visible when the circuit is broken. Circuit member 54 preferably of copper is held 100 against the inner wall of cylindrical housing 38 by rivet 55 in contact with cap 39 thereby electrically connecting said circuit member 54 and cap 39.

When there is a short circuit or overload the current passes from terminal cap 40 through screw 42 into holding nut 47, and wire 50 into holding spring 45 through circuit wire 56, then through copper circuit cap 52, into circuit member 54, rivet 55 and cap 39 thereby completing the circuit whereupon the increased current passing through wire 50 will heat it sufficiently to cause it to expand lengthwise and press outwardly against spring 45 thereby forcing lip 49 out of engagement with L-shaped bracket 43 whereupon said bracket will return to the position shown in Fig. 11 thus drawing circuit cap 52 out of engagement with circuit member 54 and circuit wire 56 and breaking the circuit while at the same time exposing the radium to view and visibly indicating that there is an open circuit.

In order to reset the device for further use it is only necessary to press fibre pin 51 inwardly thereby forcing beveled edge 43' of L-shaped member 43 past beveled edge 49' of lip 49 on spring 45 until said lip en-

gages the rear side of L-shaped member 43, as shown by dotted lines in Fig. 11, said spring thereby holding cap 52 in engagement with wire 56 and circuit member 54 thus completing the circuit.

While I have shown and described preferred and modified constructions it will be understood that my invention is not limited thereto but includes such further modifications as may be comprehended within the scope and spirit of the claims.

What I claim as new and desire to secure by Letters Patent is:

1. In an automatic cut out, a porcelain housing having a hole through one end, a porcelain cap having a hole therethrough mounted upon the other end, a screw extending therein and having a reduced stem, a fibre pin having a socket adapted to receive said stem and slidably mounted in the hole in said cap, a U-shaped bracket mounted on said screw and insulated therefrom, a holding nut on said screw insulated from said U-shaped bracket, a spring finger forming part of said bracket, and having a beveled lip, a collar fixed on said fibre pin and having a tapered shelf, a tapered conducting collar fixed on said fibre pin, an arm on said bracket, a beveled lug on said arm adapted to engage said U-shaped bracket, a tapered conducting collar fixed on said fibre pin, an arm on said bracket and a beveled lug on said arm adapted to engage said tapered collar.

2. In an automatic cut-out, a porcelain housing having a reduced end with a hole therethrough and a porcelain cap having a hole therethrough mounted upon the other end, a screw passing through said housing and having a stem extending therein, a holding nut threaded to said screw, a non-conducting pin having a socket adapted to receive said stem and a spring on said stem interposed between said non-conducting pin and said holding nut.

3. In an automatic cut out, a non-conducting housing having a non-conducting cap provided with a hole therein and means for attaching said cap to said housing, terminals mounted on said housing to form electrical connection with an electric circuit, a conducting bracket having a spring finger mounted in said housing and insulated from said terminals, a non-conducting slideable pin having a socket in one end mounted in said housing, a stem connected to one of said terminals and extending into said socket, a coil spring mounted on said stem and interposed between said terminal and said pin, a stop on said pin having a tapered flange adapted to engage said spring finger and hold said slideable pin in retracted position, a conducting arm on said bracket, a conducting lug on said conducting arm, a conducting collar on said pin, a spring circuit connection connecting one of said terminals to said collar and a conducting wire connecting the other termi-

nal to said spring finger whereby when said circuit is overloaded said wire will heat and expand thereby disengaging said spring finger from said stop and permitting said spring to slidably move said pin outwardly, substantially as set forth and for the purposes specified.

4. In an automatic cut out, a porcelain housing having a hole through one end, a porcelain cap having a hole therethrough mounted upon the other end, a screw extending therein and having a reduced stem, a fibre pin having a socket adapted to receive said stem and slidably mounted in the hole in said cap, a U-shaped bracket mounted on said screw and insulated therefrom, a holding nut on said screw insulated from said U-shaped bracket, a spring finger forming part of said bracket, and having a beveled lip, a collar fixed on said fibre pin and having a tapered shelf, a tapered conducting collar fixed on said fibre pin, an arm on said bracket, a beveled lug on said arm adapted to engage said tapered collar and a wire attached to said first named terminal and to said lip respectively, for the purposes specified.

5. In an automatic cut out adapted for operation in an electric circuit, a housing having means for forming electrical connection with a movable non-conducting pin having conducting means thereon, a finger, an electrical connection within said cut out having a wire in engagement with said finger and adapted when said circuit is overloaded, to heat and expand thereby causing said finger to yield out of engagement with a part of the circuit, and means to force said non-conducting pin away from its position in the circuit, whereby the circuit is broken.

6. In an automatic cut out, an insulating housing, means thereon comprising terminals, for forming electrical connection with an electric circuit, a spring finger, an electrical connection attached to one of said terminals and having contact with a spring electrical connection, a movable stop adapted to engage said spring finger whereby the electrical connections are held in contact, and an electrical connection between one of said terminals and said spring finger whereby when said connection is heated and expanded, it will force said spring finger out of contact with said stop and break said electrical connection.

7. In an automatic cut out, an insulating housing having a threaded terminal to form electrical connection with an electric circuit, a central terminal adapted to form contact with said circuit, a spring in said cut out, a bracket, an arm electrically connected and supported thereby, a lug on said arm, a tapered collar non-electrically mounted and adapted to contact with said lug, a stop non-electrically mounted, a spring finger, a wire

- conductor connected to said central terminal and to said spring finger whereby when said circuit is overloaded, said wire will heat and expand and force said spring finger out of contact with said stop and said spring will force said tapered collar out of contact with said lug whereby the circuit is broken, substantially as set forth and for the purposes specified.
8. In an automatic cut out, a non-conducting housing, terminals in said housing adapted to form connection with an electric circuit, a conducting bracket mounted in said housing having a spring finger and insulated from said terminals, a non-conducting pin mounted in said bracket and having radium near its outer end adapted to be concealed within said housing when the circuit is closed and to be exposed through the end of said housing when the circuit is broken, a conducting arm on said bracket, a conducting lug on said arm, a conducting collar on said pin adapted to engage said lug, a spring interposed between the end of said housing and said pin, a conducting wire connecting one of said terminals to said spring finger, a spring connection connecting the other of said terminals to said conducting collar, and a stop on said pin adapted to engage said spring finger, all for the purposes substantially as set forth.
9. In an automatic cut out, a non-conducting housing terminals mounted thereon to form electrical connection with an electric circuit, a conducting bracket having a spring finger mounted in said housing and insulated from said terminals, a non-conducting slidable pin mounted in said housing, a spring interposed between one end of said housing and said slidable pin, a stop on said pin adapted to engage said spring finger, a conducting arm on said bracket, a conducting lug on said arm, a conducting collar on said pin adapted to slidably engage said lug, a conducting wire connecting one of said terminals to said spring finger and a spring circuit connection connecting the other end of one of said terminals to said conducting collar, substantially as set forth and for the purposes specified.
10. In an automatic cut out, a non-conducting housing having a closed cap provided with a central opening and an observation hole between the center and the edge thereof, terminals mounted thereon to form electrical connection with an electric circuit, a conducting bracket having a spring finger mounted in said housing and insulated from said terminal, a non-conducting slidable pin having a key way and mounted in said housing, a spring interposed between one end of said housing and said slidable pin, a non-conducting sleeve having a knob on one end and a flange on the other end and provided with an internal key, mounted on
- said pin, a bell shaped dial fixed on the stem of said sleeve and having numbers thereon adapted to be observed through said hole, an ear on said bracket adapted to receive said sleeve and engage said flange, a conducting arm on said bracket, a conducting lug on said arm, a conducting collar on said pin adapted to engage said lug, a stop on said pin having a flange adapted to engage said spring finger and said ear, respectively, a spring circuit connection connected to one of said terminals and to said conducting collar, and a conducting wire connecting the other of said terminals and said spring finger whereby when the circuit is overloaded said wire will heat and expand thereby forcing said spring finger out of contact with said flange and permitting said spring to move said pin outwardly to engage said stop and said ear, substantially as set forth and for the purposes specified.
11. In an automatic cut out, an insulating housing having threaded terminals to form electrical connection with an electric circuit, a central terminal adapted to form contact with said circuit, a spring in said cut out, a bracket having a spring finger, an arm electrically connected and supported thereby, a lug on said arm, a collar non-electrically mounted and adapted to contact with said lug, a wire conductor connected to said central terminal and to said spring finger and partly insulated therefrom whereby when said circuit is overloaded said wire will heat and expand and force said spring finger out of contact with said stop and said collar out of contact with said lug whereby the circuit is broken.
12. In an automatic cut out, a non-conducting housing having a central opening in one end and an observation hole therethrough, a sleeve having a knob on one end and a flange on the other end mounted in said hole, a bell shaped dial fixed on said sleeve and having numbers thereon adapted to be observed through said observation hole and having depressions therein and a spring mounted in said housing and adapted to engage said depressions whereby said dial is held in adjusted position.
13. In an automatic cut out, a non-conducting housing having a central opening in one end and an observation hole therethrough, a sleeve mounted in said opening, a dial mounted thereon and adapted to move therewith and having numbers thereon adapted to be observed through said observation hole and means for holding said dial in adjusted position.
14. In an automatic cut out, a non-conducting housing having a hole in each end, a threaded terminal on said housing, a central terminal mounted in one of said holes and having a stem extending inwardly therefrom, a non-conducting pin having a

- socket in its inner end adapted to receive said stem and mounted in the other of said holes, a stop on said pin, a conducting bracket having a spring finger mounted on 5 said central terminal and insulated therefrom, a holding nut mounted on said central terminal and insulated from said bracket, a spring on said stem interposed between said nut and said pin, a conducting wire connected to said nut and to said spring finger, a conducting arm on said bracket, a conducting lug on said arm, a conducting collar on 10 said pin and a spring circuit connection attached to said threaded terminal and having its free end curved and adapted to engage said collar, substantially as set forth and for the purposes specified.
15. An automatic cut out comprising an insulating housing, terminals therefor, a conducting bracket mounted in one of said terminals, an arm on said bracket, a tapered lug on said arm, an insulating slidably mounted pin having a stop thereon and socket therein, a tapered conducting collar fixed on said pin and adapted to engage said lug, a spring 20 conductor attached to the other terminal and adapted to form contact with said collar, a spring finger forming part of said bracket and having a lip adapted to engage said stop, a stem on said first named terminal 25 adapted to engage said socket, a spring on said stem interposed between said terminal and said pin, a conducting wire connected to said first named terminal and to said spring finger, whereby when the circuit thus 30 formed is overloaded said wire will expand and force said spring finger out of engagement with said stop and said spring will force said collar out of contact with said lug and said stop away from said spring 35 finger whereby the circuit is broken.
16. An automatic cut out comprising an insulating housing, terminals therefor, a conducting bracket mounted in one of said terminals, an arm on said bracket, a lug on 40 said arm, an insulating slidably mounted pin having a stop thereon and socket therein, a tapered conducting collar fixed on said pin and adapted to engage said lug, a spring 45 conductor attached to the other terminal and adapted to form contact with said collar, a spring finger forming part of said bracket and having a lip adapted to engage said stop, a stem on said first named terminal 50 adapted to engage said socket, a spring on said stem interposed between said terminal and said pin, a conducting wire connected to said first named terminal and to said spring finger, whereby when the circuit thus 55 formed is overloaded said wire will expand and force said spring finger out of engagement with said stop and said spring will force said collar out of contact with said lug and said stop away from said spring 60 finger whereby the circuit is broken.
17. A non-conducting housing having a hole in one end, a terminal therethrough, a rod integral with said terminal and extending within said housing, a spring finger connected to the terminal but insulated therefrom, a wire forming an electrical connection to said terminal which when overloaded will expand and disengage said spring finger 65 from said rod.

ERNEST MEIERJOHAN.
